UNITED STATES PATENT OFFICE.

ELIAS E. RIES, OF NEW YORK, N. Y., ASSIGNOR TO THE UNITED STATES AUTOMATIC TELEPHONE COMPANY, OF NEW YORK.

AUTOMATIC TELEPHONE.

SPECIFICATION forming part of Letters Patent No. 639,291, dated December 19, 1899.

Application filed August 7, 1897. Serial No. 647,455. (No model.)

To all whom it may concern:

Be it known that I, ELIAS E. RIES, a citizen of the United States, and a resident of New York, in the county and State of New York, 5 have invented certain new and useful Improvements in Automatic Telephones, of which the following is a specification.

My invention relates to certain improvements in telephone-receivers having a self-contained automatic switching device by means of which the circuit connections are automatically changed from the signaling to the conversational condition by the natural operation of lifting the receiver to the ear 15 and are restored to the signaling condition by permitting the receiver to come to rest in its normal position.

My present invention is primarily designed as an improvement upon the telephone-switch 20 shown in my United States Patent No. 567,794, dated September 15, 1896, although in some of its features it is applicable to other forms of apparatus. In that patent, as in the present case, I have shown and described a device 25 which dispenses with the use of hook-switches by combining with the receiver a gravity-switch in which the circuit-changing medium consists of a small quantity of mercury or other mobile conducting medium contained 30 within a suitably-sealed chamber or receptacle, the arrangement being such that the act of lifting the receiver to the ear will automatically cause the said medium to shift its position from the space or portion of the chamber 35 where it is retained in position to complete the calling-circuit to the portion of the chamber or space where it is retained in a position to cut in the receiver-coil and the transmitter with its battery, while the dropping of the receiver or the act of replacing or suspending it in its normal or vertical position while the apparatus is out of use will instantly restore the connection for calling or receiving a calling-signal by causing the mercury or other 45 medium to flow by gravity from the chamber where it is retained when the instrument is in position for conversation through a suitable path or passage to the chamber where it is retained in position to cut out the transmitter and receiver and cut in the calling 50 circuit.

The object of my present improvement is, first, to insure greater certainty and reliability in the operation of the circuit-changing apparatus by providing for a wider range of movement or permissible tilting of the receiver while the latter is being used with the circuits in the conversational position; secondly, to adapt the invention to telephone-receivers of a more compact type—such, for example, as the class commonly known heretofore as “watchcase-receivers”—in connection with which my invention is designed to provide a convenient knob or holding device by which such receivers may be more readily manipulated, and, thirdly, in providing a certain novel and useful means whereby a calling signal may be sent over the line by the person using my automatic telephone either preparatory to or during the process of using the instrument without recourse to and independently of the usual magneto calling apparatus, thus greatly facilitating the process of telephonic communication and at the same time not only simplifying the construction and reducing the cost of a subscriber's outfit, but, by dispensing with the stationary or fixed gravity-hook switches or supports heretofore employed and combining the various instrumentalities for signaling, switching, and receiving in the form of a single portable apparatus in which these various operations are rationally and naturally performed, especially adapting the same to desk, office, household, and other uses, both for interior and long-distance circuits, to which uses existing types of telephonic apparatus are more or less inapplicable and objectionable.

In the drawings, Figure 1 is a sectional elevation of one form of my improved automatic telephone-receiver in its normal position, showing the form and arrangement of the conical mercury or switch chamber and the calling apparatus. Fig. 2 is a plan view of the same with the upper cap-piece and the calling apparatus and its connections removed. Fig. 3 is a detailed plan view of the main switch-contact cup containing the auxiliary calling apparatus and showing the circuit connections. Fig. 4 is an enlarged detail, in part, of the knob containing the calling apparatus, mercury-chamber, and switch-contact.

ing a slightly-modified construction. Fig. 5 is a diagram showing the arrangement of the circuits and their connection with the respective binding-posts of the instrument, the auxiliary calling-circuit being shown in dotted lines. Fig. 6 is a detailed plan view of the upper switch-contact rings shown in Figs. 1 and 2. Fig. 7 is a sectional elevation, and Fig. 8 a plan with cap removed, of a modified type of my automatic telephone in which the circuit connections are brought out at the top instead of at the side of the instrument and showing the mercury-switch and its connections as the same are arranged without the auxiliary calling device. Fig. 9 is a detail sectional elevation, and Fig. 10 a plan view, showing the preferred construction of this type of instrument when the calling device is employed. Fig. 11 is a diagram similar to Fig. 5, showing the various telephone circuit connections. Fig. 12 is a detailed view of the mercury-chamber as it appears when inclined in the position assumed in the act of listening. Fig. 13 is a skeleton diagram showing the interior connections between the various switch and receiver terminals and the binding-posts.

Similar letters of reference represent corresponding parts in the various figures.

Referring to Fig. 1, E is the earpiece of a telephone-receiver of any approved type. In the present instance the type of instrument shown is that known as a "pony" or "watch-case" receiver, in which the central core F and the inclosing shell F', together with the diaphragm D, constitute the magnetic circuit through which pass the lines of force, the strength of which is varied by the currents induced in the receiver-coil C. The rear or upper end of the core F in this figure is provided with a conical or cup-shaped cavity v, which serves as the receptacle for a small quantity of mercury or quicksilver Q. A knob-shaped block K, of hard rubber or other insulating material, is secured to the top of the magnet-shell F' by the threaded end of the core F, and this block is provided with a conical central opening constituting a flaring chamber whose sides form a continuation of the angle formed by the cavity v. The sides of this chamber are preferably inclined at an angle of forty-five degrees from a perpendicular line through the axis of the instrument, for reasons that will presently appear, (although any other desirable angle may be used,) but toward the upper portion of the chamber are preferably continued in a perpendicular direction, so that at its widest portion the walls of the chamber are cylindrical. Nesting within this chamber and supported by its flange at the top of the block K is a conducting-shell Y, preferably of iron, (or any other metal not attacked by mercury,) whose sides are inclined to conform with those of the block-chamber, but are of somewhat smaller dimensions, so as to leave an annular

conically-shaped space between them, which constitutes the mercury-chamber q.

Embedded in the upper portion of the block K, with their inner surfaces flush with the mercury-chamber q, are two contact-rings W X, also of iron, slightly separated and insulated from each other by the material of the block K if the latter is molded with the rings in place, or by a separating-ring of insulating material if the construction shown in Fig. 4 is used. Between the upper ring W and the flange of the shell Y may be interposed an insulating ring or gasket o, which serves to seal the mercury-chamber when the shell Y is secured to the block by the screws o' o'. An insulating cap-piece K', which screws upon a peripheral thread formed in the block K, further serves to hold and inclose the various parts, and together with the block K forms a convenient knob or grip for manipulating and holding the receiver.

Under certain conditions, which will presently be more fully described, I provide the interior hollow portion of the conducting shell Y with a small auxiliary switchboard J, Figs. 1 and 3, to the upper surface of which are secured three contact springs or surfaces. The contact-spring J' normally rests against the back contact J", but is caused to break its connection with J" and to establish connection with the contact-surface A' when pressure is brought upon the knob or key k. This key passes freely through the center of the cap-piece K' and has an elongated stem and a button-shaped head which serves both as a push-button and as a support for conveniently hanging the instrument, if desired, upon a suitably-shaped hook or fork k'. (Shown in dotted lines.)

The flange of the shell Y, which forms the main-line terminal, is connected by means of a small conducting pin or bolt y and by wire y' to the binding-post L, which forms one of a number that are screwed with interposed bushings to one side of the inclosing shell F'. As will be seen by reference to the diagram Fig. 5, this binding-post L connects to the line. The bolt y, as will be seen, passes through one of a number of vertical holes h, (six in Figs. 2 and 3,) which are preferably located at equal intervals around the knob K directly under the contact-rings W X. The latter have their outer edges cut away, as shown in Fig. 6, or may be drilled after assembling and provided with insulating-bushings h", as shown in the construction illustrated in Fig. 4, in order to permit of the free passage of the various conducting pins or bolts without touching the same at such points as require a through connection between the space above the shell Y and the space within the inclosing shell F'. The upper contact-ring W connects by means of the pin u and wire w' with one end of the coil C of the receiver. The other end of this coil connects by wire s" to the binding-post S, which, as will be seen

from the diagram view, is in connection with the secondary coil s' of the transmitter. The lower contact-ring X is connected by a pin x at the back of the receiver and wire x' with the binding-post B , which leads to the primary coil, transmitter, and battery. The binding-post M , which leads to the magneto and call bell, is, when the auxiliary switchboard J and its connections are omitted, as in Fig. 2, directly in electrical connection with the inclosing shell F' , with which the mercury-cavity v makes connection. When the switchboard or calling apparatus J is employed, however, an auxiliary binding-post A , Fig. 5, is provided, and instead of connecting the binding-post M directly to the magnet-shell F' the same is likewise insulated from the shell and connected through wire m' , by means of the vertical connecting-pin m and wire m'' , to the back contact J'' of the spring J' of the switchboard J . The spring J' in turn connects by a wire j' with the vertical pin j , which screws into the magnet-casing F' . The additional insulated binding-post A is connected by a wire a' and a vertical pin a , Fig. 3, to the lower contact A' , that is screwed to the insulating-block J . It will be observed that the effect of this arrangement upon the circuit connections under normal conditions is the same as though the switchboard J were omitted, since owing to the bridging of the contacts J' and J'' there is a direct conducting-path through the mercury Q , when resting in the cavity v , to the magneto binding-post M , while the auxiliary post A under these conditions is practically dead due to the open-circuiting at its terminal contact A' . The various wires connecting with the binding-posts of the instrument are preferably brought together into a single flexible cord c , which is supported within a suitable bracket extension c' at one side of the instrument, as shown in Fig. 2.

The operation of my automatic telephone, so far as described, will now be apparent.

Neglecting for the time being the auxiliary calling-switch feature we will assume that the instrument is used at one end of a telephone-circuit provided with the usual transmitter, induction-coil, local battery, and magneto calling apparatus, as indicated in full lines in Fig. 5. If now the telephone is standing or hanging in its normal position, as shown in Fig. 1, the mercury Q will rest at the bottom of the conical mercury-chamber q within the cavity v of the core F , thus making connection between the lower end or tip of the main-line contact-shell Y , which is connected with the line through binding-post L , and the core and shell F' , which connect with the magneto through binding-post M . The receiver-coil, as well as the transmitter and its local battery, is open-circuited under these conditions by reason of the absence of the mercury from the two upper contact-rings W and X . Consequently the connections are in the condition for signaling, and a call may be

sent over the line by operating the crank of the magneto M' , or an incoming call may be received upon the local magneto or signal bell M'' . When the calling-signal has been either given or received, the receiver is taken by the knob or switch-block K and lifted to the ear. This action causes the mercury to at once run to the opposite or upper end of the switch-chamber, as shown in the detail view, Fig. 12, breaking connection with the metal surface of the lower contact-cavity v and establishing the connection between the main-line contact-shell Y at what is now its lowest point and the two contact-rings W and X , that surround it. In this position of the telephone the magneto or calling circuit is cut out and the connections placed in the proper condition for conversation by the automatic cutting in of the receiver-coil, transmitter, and battery. Under the conditions just stated the main-line circuit is established from the line through binding-post L to contact-shell Y , through mercury Q , upper contact-ring W , receiver-coil C , binding-post S to the secondary S' of the induction-coil, and from thence to the distant station via earth G or line return. At the same time the local-battery or transmitter circuit is closed from one pole of the battery B' through line and binding-post L to the contact-shell Y , through mercury Q , lower contact-ring X , binding-post B to the primary P' of the induction-coil, transmitter T' , and the other terminal of the battery B' . By reason of the conical form and divergent sides of the mercury-chamber and main contact-surface, which arrangement forms an important part of my present invention, I obtain not only a rapid movement of the mercury from one position to the other, but I also secure the important advantage of overcoming the prior limitation of a restricted head motion by providing for a wide range of permissible inclination of my automatic receiver when held to the ear while engaged in conversation, without obliging the user to hold it in a fixed position and without danger of accidental interruption of the connections by reason of an undue tilting or inadvertent shifting of the telephone, and which is especially likely to take place in the case of the watchcase type of receivers illustrated. This is primarily due to the fact that when the instrument is in normal position for conversation the path or passage over which the mercury or other medium must flow in order to change the connections back from condition for conversation to normal condition for calling is inclined or directed upwardly. This upward direction or inclination of the passage between the two spaces in which the mercury is retained when the instrument is in position for conversation and for calling, respectively, forms an important feature of my invention, and while I prefer to employ what I have termed a "conical chamber" for the purpose, the extremes of which constitute the

mercury-retaining spaces, I do not limit myself to such form of chamber and connecting passage or path, the gist of the invention being the passage or path upwardly inclined or directed from the space occupied by the mercury or other medium when the instrument is in normal position for conversation. By reference to Fig. 12 it will be seen that it is not even necessary with this construction to hold the receiver, in listening, with its rear or top portion inclined below a horizontal line, since the tapering sides of the mercury-chamber, which, as already stated, are inclined at an angle of forty-five degrees from the longitudinal axis, will permit a decided forward inclination of the earpiece before the mercury-level reaches the magneto or calling contact-surface. This angle may be, if desired, increased or diminished, according to the type of instrument used, and the space toward the rear of the mercury-chamber is by preference so reduced in width that a small quantity of mercury will suffice to spread over a large surface of the contact-rings, and thus insure an excellent electrical connection of exceedingly low resistance. For a similar reason the main contact-shell may be provided with a central elongation or tip at its lower extremity, so as to dip farther into the mercury-cavity *v*, as shown in Fig. 1. I have found by experiment that mercury, either by itself or with the addition of a little powdered graphite, forms a most reliable and permanent conductor when used as a circuit-changing medium under the conditions herein shown, and possesses many advantages as a bridging-conductor over the ordinary circuit-changing contacts or springs. I do not, however, desire to limit myself herein to the use of mercury, as I may use small lead shot or any other finely-divided conducting material or fluid as the circuit-changing medium.

Having now described the operation of the automatic switch feature of my improved receiver, I will proceed to briefly outline the operation of the auxiliary calling device already referred to.

It will be evident that in the operation of my portable telephone it is desirable that some means should be provided for calling the party with whom one is desirous of conversing, and especially of repeating a calling-signal after a conversation is commenced without the necessity of hanging the receiver upon a hook-switch or of having recourse to a separate and sometimes distantly-located appliance, such as the ordinary magneto-generator crank or its equivalent. It is to supply this need in locations where the conditions for its use are favorable that the auxiliary calling feature of my invention is brought into play. This calling device will be also found of great use in code-signaling for party-line work.

Referring to the diagram Fig. 5 it will be seen that the auxiliary or supplementary binding-post *A* is in communication with

any constant independent source of current through the auxiliary wire or loop *A''*, (shown in this figure in dotted lines,) the opposite end of this wire or loop being joined to the wire leading to the post *M* at a point between said post and its junction with the signal-bell *M'''* and magneto *M'*, which latter, as is customary, has its coils short-circuited when not in use. In the present instance the independent source of current is shown as being supplied by secondary coil *i* of a small induction-coil or converter *I*, whose primary or inducing coil *i'* is, in connection with a generator *I'* of alternating or intermittent current, adapted to operate the bell *M'''*. The induction-coil *I* may be connected, as shown, with any convenient alternating-current lighting-circuit, or a separate intermittent current-generator capable of directly furnishing current to a number of telephone instruments located in the same building may be installed. For short-distance work or for telephone installations in which a battery calling outfit is commonly employed a battery *b* or other source of continuous current (shown in dotted lines in Fig. 11) may be substituted for the generator *I'* and induction-coil *I*.

In using my automatic telephone (which in practice is preferably arranged to lie within easy reach upon the desk or table, with the earpiece down, as in Fig. 1, the transmitter being located in a position where it is not in the way, but is at the same time within easy reach of the voice) the person desirous of establishing communication with "central" or with a distant station simply reaches out and grasps the instrument by the knob *K* preparatory to lifting it to the ear, at the same time pressing the key *k* and keeping the latter depressed for a moment or during the interval required to carry the receiver to the ear. The pressure upon the key *k* is made by one or more of the fingers, which are permitted to rest naturally upon the key while assisting the other fingers and the thumb in holding the instrument in the hand. In this movement of the receiver a calling-signal is thus transmitted to the distant station from the auxiliary source *I* by reason of the opening of the branch *M''* of the magneto-circuit at the back contact *J''* and the substitution of the auxiliary loop *A''* by the closing of the circuit between *J'* and *A'*, while the mercury *Q* still rests within the cavity *v*.

The flow of current may be traced as follows: commencing from the secondary terminal *i*, along wire *A''* to post *A*, interior connections *a' a a''* to contact-spring *A'*, thence to spring *J'*, connections *j' j*, and magnet-casing *F* to cavity *v*, thence through mercury *Q*, main shell *Y*, connections *y y'* to binding-post *L*, to line *L''*, through bell of distant station to return-wire or ground *G'*, across the normally-shunted coils of magneto *M'*, and through local bell *M'''* to opposite terminal of the secondary coil *i*. On raising the receiver to the ear this auxiliary calling

circuit is automatically interrupted by the mercury running toward the rear or base of the cone-shaped mercury-chamber q , as already described, so that the instrument will 5 then be in a condition for conversation whether the key k is kept depressed or not. Should it be desired, as is frequently the case, to repeat a call to central while awaiting an answer to the original call, it will not be 10 necessary, as under the systems now in vogue, to remove the phone from the ear and to hang it upon a switching-hook in order to restore the calling connection, thus running the risk of missing an answer to the original call; but 15 instead a slight momentary inclination or tilting of the rear portion of the receiver, the pressure upon the key k having been naturally maintained in grasping the instrument, while still engaged in listening is all that is 20 needed in order to repeat the call, thus saving a great deal of valuable time and inconvenience both to the subscriber and the central station. After conversation is once under way the pressure upon the key k may be 25 released. This cuts out the loop A'' and restores the continuity of the magneto-circuit M'' , so that when the instrument is again placed upon the desk, or, if preferred, hung by the knob K or the key k upon a suitable 30 stationary fork, at the end of the conversation the connections will be in condition to receive a call upon the bell M''' from a distant station. It will be understood that in cases where the auxiliary loop A'' is employed 35 the magneto M' may be entirely dispensed with, this portion of the drawing being intended to show the application of my device to existing installations.

On Sheet 2 I have shown a modified form 40 of my invention, in which instead of bringing the various terminals to binding-posts at the base of the instrument I bring them to a series of posts at the top of the receiver, with which connection is made by the conducting- 45 cord c , that passes out through a central opening at the top of the cap-piece, as shown in Fig. 7. This form is for some purposes a more desirable arrangement, especially since the conducting-cord c may itself form a convenient support for sustaining the instrument, 50 while the cap-piece K' serves as a protecting hood or cover for the binding-posts and conductor-terminals, none of which are exposed. In this figure I have shown a type of receiver 55 having a double pole-magnet F , the knob K and receiver-casing being formed of one integral piece of hard rubber or other insulating material, as shown. The main-line contact-shell Y in this instance forms a lining 60 for the body of the mercury-chamber q , while the conducting-rings W X are carried by an interior non-conducting block N , which at its lower extremity carries the magneto contact-terminal V , which latter is secured to the screw 65 or bolt n' , which in the plan view Fig. 8 which shows the terminal arrangement when the

auxiliary calling feature is dispensed with, is connected by conducting-strip n'' with the rear binding-post M . As shown in this figure, the binding-posts M , L , B , and S are set 70 around the block N directly above the contact-rings, leaving a central space which may be occupied by a supporting-knot in the conductor-cord c . The post B screws into the lower ring X , while the others simply enter 75 for a short distance the block N , the various terminal wires being brought up to them from the receiver-casing through holes h' , formed in the insulating-blocks K and N . A terminal screw R , which is tapped into the upper 80 contact-ring W , connects this ring by wire w' with the receiver-coil, the other electrical connections leading from the various contacts being the same as already described with reference to the previous figures. 85

In Figs. 9 and 10 I have shown the terminal arrangement when the auxiliary calling device is used. The central key k is somewhat enlarged and in the form of a sleeve or bushing, being provided with a hollow central 90 opening having a number of lateral branches k'' , through which the conductors of the cord c pass to the binding-posts of the instrument. This key has a lower closed portion bearing upon the spring J' , which is in connection with 95 the contact V through the central screw n' . The key k is formed of two parts and, as shown in Fig. 4, may be pressed upwardly by a separate spiral spring k''' , so as to relieve the spring J' of this duty. The key has a 100 free vertical motion around the conducting-cord c and is readily manipulated by the pressure of the fingers which straddle the cord when the receiver is grasped in the hand. The binding-posts M L B S A , and their connections in the plan view Fig. 10 are identical with those already described in connection with the preceding figures, and the circuit connections as they exist under the alternate positions of the mercury-chamber 110 (shown, respectively, in Figs. 7 and 12) may likewise be traced by reference to the diagram view Fig. 11. In order to further facilitate the tracing of the different circuits, I have shown in Fig. 13 a skeleton diagram of the 115 various parts of my automatic receiver with the interior connections to their respective binding-posts.

When my improved telephone is to be employed for short-distance work or under conditions where a battery instead of a magneto calling apparatus is usually installed, as already stated, a calling-battery b , wired up as shown in dotted lines in Fig. 11, will take the place of both the magneto M' and the auxiliary source I and will serve when connected between the conductors A'' and M'' to automatically perform its calling functions when my receiver is taken in hand upon entering into conversation, as well as automatically "ringing off" when the conversation is ended. 130

While I have herein shown my invention as applied to certain specific forms of telephone-receivers, it will be understood that its principle is such that it can be applied to any type of telephone-receivers—such, for example, as is illustrated in my previous patent— as well as to any condition of telephone-circuits, and I therefore do not desire to limit myself to its application to the particular type 5 of receivers or circuit connections illustrated. I may also in cases where this is desirable suitably combine in one and the same apparatus, so as to constitute an integral part of the portable instrument herein shown and described, the transmitter T, with its induction-coil and the calling bell or buzzer M'', leaving only the circuit connections to the line and battery to be provided for outside of the instrument proper.

20 From what has been said it will be evident that by means of my invention a simple, rational, self-contained, and effective telephone of great flexibility is provided, that reduces the number of the manual operations required 25 by and affords many other advantages over the existing methods of conducting telephonic communications and the more or less complicated apparatus for practicing the same, inasmuch as by means of my automatic telephone only a single movement of a single hand, (leaving the other entirely disengaged,) and that movement promptly and almost unconsciously performed in a most natural and instinctive manner without any necessary 30 previous training, is all that is required to commence, carry on, and finish a conversation.

In my prior patent, No. 567,794, I describe a switching-chamber of cylindrical or tubular form, one extremity of the tube or cylinder 40 constituting a mercury-chamber in which the mercury rests when the instrument is out of use and said extremity being of conical or tapered shape. In this form of switch when the instrument is held in the normal position 45 for use—that is to say, in the horizontal position—the mercury is apt to flow into the conical end and there make the signaling or calling connection unless pains be taken to slightly invert or incline the instrument in 50 the opposite direction. This form of chamber differs, essentially, from my form in which the sides are conical or flaring, so that when the instrument is held in horizontal position the mercury being at one end of the chamber 55 can only reach the other end by flowing up the inclined side, and hence the instrument may be used in the normal way without danger of changing the connections.

Having thus described my invention, what 60 I claim, and desire to secure by Letters Patent, is—

1. In an apparatus for telephonic communication, a single portable apparatus embodying the signal-controlling device and circuit-changing and receiving mechanism, of a tele-

phone-station combined as described to successively perform their signaling, circuit-changing and receiving functions by the act of grasping and lifting the said apparatus to the ear.

2. In an apparatus for telephonic communication, a single portable instrument comprising a telephone-receiver bearing a self-acting or gravity switch that automatically changes the connections from condition for 70 receiving the signals to condition for conversation, and also a signal-controlling device for calling the distant station adapted to be grasped or engaged by the hand when taking hold of the instrument, whereby, as described, 75 the calling, circuit-changing and receiving functions are successively performed by and in the act of grasping and lifting the said apparatus to the ear.

3. In a telephonic apparatus, a telephone 85 receiver or earpiece carrying a gravity circuit-changing switch together with a complementary signaling-switch or circuit-controlling device adapted to operate in conjunction therewith, all combined and constructed as 90 described to perform the calling, circuit-changing, receiving and ringing-off functions by the act of grasping the receiver, applying the same to the ear and returning or permitting it to return to its normal position when 95 the conversation is ended.

4. In a telephone system, the combination with the local call-bell and a magneto-generator or other normally-inactive source of calling-current, of a switch device for normally 10 maintaining the local circuit closed through said bell so that the latter may be operated by a calling-signal transmitted from such normally-inactive source, and an independent or auxiliary active source of calling-current and a local-circuit-closing key therefor designed and adapted to transmit a calling-current and to operate the call-bell when manipulated while the said switch is in its normal condition, substantially as set forth.

5. In a telephone system, the combination, with the signaling-circuit and a switch device for normally maintaining said circuit in a condition to be responsive to a calling-current sent over the same from a distant and 115 normally-inactive source, of a continually-active auxiliary generator, and an auxiliary key or push-button arranged to be operated in conjunction with said switch device for including said auxiliary generator in the signaling-circuit, substantially as set forth.

6. In a telephone system, the combination with the signaling-circuit and a normally-inactive magneto-generator included therein, of an auxiliary continually-active source of 125 alternating or intermittent current, and means located upon the receiver for including said source in the signaling-circuit, substantially as and for the purpose set forth.

7. In a telephone system, the combination 130

- with the signaling-circuit and a normally-inactive source of signaling-current therefor, of an auxiliary continually-active source of signaling-current, and a key upon the receiver for including the auxiliary source of current in the signaling-circuit, substantially as and for the purpose set forth. 5
8. In a telephone system, the combination with the signaling-circuit, of a continually-active source of current therefor normally disconnected, and means located within or carried by the receiver and operated by the action of inclining or tilting the receiver while the same is grasped by the hand and held in position for listening, as described, for operatively including the said source in the signaling-circuit and thus repeating the call while awaiting an answer to the original call. 15
9. The combination with a telephone-receiver carrying an automatic gravity-switch for changing the local circuits automatically from condition for receiving a signal to condition for conversation, of an auxiliary key or switch device, and a continually-active generator controlled thereby for transmitting a call. 20
10. In a telephone system, the combination with the signaling-circuit and a switch device for normally maintaining said circuit in condition to be responsive to a calling-current, of a continually-active generator, and an auxiliary switch or key independent of the telephone-support for transmitting a signaling-current from said generator. 25
11. In a telephone system, the combination with the local call-bell, of a switch device for normally maintaining the local circuit closed through said bell so that the latter may be operated by a calling-signal sent from a distant point, a source of calling-current, and a local-circuit-closing key therefor designed and adapted to transmit calling-current when manipulated while the said switch is in its normal condition. 35
12. In a telephone system, the combination with the signaling-circuit, of a switch device for normally maintaining said circuit in position to be responsive to a calling-current sent over the same from a distant source, a continually-active auxiliary local generator, and an auxiliary key or push-button arranged to be operated in conjunction with said switch device for including said auxiliary generator in a signaling-circuit through said switch device while the same is in its normal position. 45
13. A telephone-receiver bearing a gravity-circuit changing or switching device, and having a calling-key connected to said switching device, as described, so as to be rendered operative when said switching device is in one position and to be thrown out of operative condition when said switching device or the receiver containing the same is in another position, substantially as and for the purpose set forth. 55
14. An automatic telephone instrument comprising in a single portable structure, a receiver, a circuit-changing switch adapted to be automatically operated by the change in position of the receiver from the calling to the listening position and vice versa, and a key or signaling device arranged to be operated for transmitting a calling-current by the hand which grasps the receiver, substantially as set forth. 60
15. A telephone-receiver bearing a mercury-chamber, a series of contact-surfaces within said mercury-chamber, connections between said contact-surfaces and a series of binding-posts carried by or secured to the body or frame of the receiver, and a calling key or switch interposed between one of said contact-surfaces and one or more binding-posts, connected with or included in the signaling-circuit; substantially as and for the purpose set forth. 65
16. A telephone instrument having a receiver coil and diaphragm and a casing therefor, an insulating-knob at the back of said receiver-casing containing an automatic gravity circuit-changing switch and an auxiliary signal or calling device, and an inclosing cover or cap-piece for said device containing a key or push-button for operating the same, substantially as set forth. 70
17. In a telephone-receiver, the combination of an inverted-cone-shaped conducting cup or shell having a cylindrical upper or base portion and serving as the receptacle for a fluid conductor, an insulating plug or stopper having a lower portion substantially conforming in shape to and entering said conducting-shell and carrying supplementary conducting-terminals, a fluid or similar circuit-closer, as described, a circuit-closing switch mounted upon the upper or exterior portion of said insulating-plug, an inclosing cover for the circuit-closing switch and receiver-terminals, and a key or button projecting through said inclosing cover for operating the circuit-closing switch, substantially as set forth. 75
18. In a telephone-receiver, the combination with the knob or casing containing the gravity-switch and calling-contacts and their connections, of an inclosing cover or cap-piece containing a movable key or signaling-button operating upon said contacts, substantially as set forth. 80
19. In a telephone-receiver, the combination with the knob or casing containing the gravity-switch and calling-switch contacts and the terminal binding-posts, of an inclosing cover or cap-piece for the same, and an operating calling key or button carried by said cap-piece and having an opening or openings for the passage of the conducting-cord leading to the binding-posts. 85
20. In a telephone-receiver, the combination with the calling-switch or circuit-closer 90

having a front and back contact, the receiver binding-posts and their inclosing cover having a central opening, of the combined conducting-cord bushing and operating key for said calling device movable within said opening, substantially as set forth

In testimony that I claim the foregoing as

my invention I have signed my name, in presence of two witnesses, this 31st day of July, 1897.

ELIAS E. RIES.

Witnesses:

Wm. H. CAPEL,
H. HOFFMAN.
